US0D1112729S

(12) **United States Design Patent** (10) **Patent No.:** **US D1,112,729 S**
(45) **Date of Patent:** **** Feb. 10, 2026**

(54) **A-FRAME CONNECTOR**

(71) Applicant: **P&P IMPORTS LLC**, Irvine, CA (US)

(72) Inventors: **Peter Engler**, Newport Beach, CA (US); **Peter Tanoury**, Newport Beach, CA (US); **Willis Santamaria**, Diamond Bar, CA (US)

(**) Term: **15 Years**

(21) Appl. No.: **29/800,031**

(22) Filed: **Jul. 19, 2021**

(51) **LOC (15) Cl.** **21-02**

(52) **U.S. Cl.**

USPC **D21/686**; D21/454

CLAIM

The ornamental design for an a-frame connector as shown and described.

DESCRIPTION

FIG. 1 is a perspective view of the a-frame connector showing the claimed design;

FIG. 2 is a right-side elevational view of the a-frame connector thereof, the left-side elevational view being a mirror image thereof;

FIG. 3 is a front elevational view of the a-frame connector thereof;

FIG. 4 is a back elevational view of the a-frame connector thereof;

FIG. 5 is a top plan view of the a-frame connector thereof; and,

FIG. 6 is a bottom plan view of the a-frame connector thereof.

The broken lines in the figures show portions of the a-frame connector that form no part of the claimed design.

1 Claim, 6 Drawing Sheets
